FINGER-BOARD TIP

Joe E. Nichols, Coalinga, Calif.

Application December 12, 1938, Serial No. 245,331

5 Claims.

(Cl. 211—60)

This invention relates to a pipe racking attachment for use in an oil well drilling derrick and particularly to a fingerboard having a selectively movable tip which is used to control the removal of lengths of drill pipe which are standing in the derrick.

Heretofore it has been the practice to provide a fingerboard which is a substantially horizontal member extending toward the middle of the derrick from one of its sides and against which the lengths of drill pipe, casing and the like, which are to be introduced into the well bore are racked. As each pipe is removed it is slid outwardly over the tip of the fingerboard and picked up by the elevators of the hoisting equipment. Various hand-operated arrangements of pivoted dogs and the like have been proposed, all of which require that the derrickman remove one hand from the length of pipe which he is handling and manipulate the fingerboard tip. This constitutes a safety hazard as the lengths of drill pipe weigh several tons and, while they are standing on end, are oftentimes difficult to handle as rapidly as good drilling practice may require.

It is an object of this invention to provide a tip or latch for the end of this fingerboard so that the operator standing in the derrick may release a section of pipe without having to use his hands and without danger to himself.

Another object is to provide a tip for a fingerboard which may be automatic in its action so that the drill pipe being handled will serve to actuate it to its extended or operative position.

Another object is to provide a simple and strong form of fingerboard tip that contains a minimum of moving parts.

These and other objects and advantages of this invention will be more fully apparent from the following description and the accompanying drawing which illustrates a preferred embodiment of the device together with an alternative form which is more simple in construction.

In the drawing:

Figure 1 is a plan view of the automatic embodiment of the fingerboard tip in position to retain a length of drill pipe.

Figure 2 is a plan view of the fingerboard tip illustrated in Figure 1 but in its inoperative position.

Figure 3 is a side elevation view of the fingerboard tip of Figure 2.

Figure 4 is a vertical sectional view on line IV—IV of Figure 1.

Figure 5 is a vertical sectional view on the line V—V of Figure 2.

Figure 6 is a vertical sectional view on line VI—VI of Figure 3.

Figure 7 is a plan view of a simpler embodiment of this invention showing the fingerboard tip in

its open or extended position to retain a length of drill pipe.

Figure 8 is a side elevation view of the fingerboard tip of Figure 7.

5 Figure 9 is a diagrammatic plan view of a fingerboard tip embodying this invention in place in a conventional drilling derrick.

Referring to Figure 9, reference numeral 10 indicates the corner legs of a conventional well 10 drilling derrick joined together by horizontal girts 11. A platform represented by 12 rests across girts 11 at a suitable height to receive a number of lengths or stands of drill pipe 13. The drill pipe is stacked or racked in one corner 15 of the derrick frame behind a fingerboard 14 which is provided with a tip generally designated 15. Traveling block 16 is adapted to support elevators (not shown) which pick up single lengths of drill pipe 13 and lift them into position 20 to be coupled with or uncoupled from drill pipe already in place in the well bore.

In order to control the lengths of drill pipe 13 which may be 90 or 120 feet in length, fingerboard tip 15 is provided with means which may 25 be selectively extended horizontally as shown in Figure 9 to hold a single length of drill pipe 13 in position to be picked up by the traveling block and elevators, and to release that length of drill pipe when the elevators are lifted.

30 This invention broadly comprehends an improved tip for fingerboard 15 which is actuated by the force of gravity or by contact of the drill pipe against a lever, either of which serves to extend horizontally a hook or latch element which 35 will retain the drill pipe and prevent it sliding past the end of the tip.

Referring to Figures 1 to 6 which illustrate the preferred embodiment of this invention, reference numeral 17 designates the outer end of fingerboard 14 to which is secured a hollow body 18 which may be roughly rectangular in cross section. A shaft 19 extends longitudinally of body 18 and is journaled in any suitable manner 40 to rotate therein. The outer end of shaft 19 is bent substantially at right angles to form a hook or latch member 20 which may be extended horizontally from body 18 to prevent a stand of pipe from slipping past the end of the fingerboard structure. The body 18 is preferably provided 45 with an abutment 21 which will prevent hook 20 from moving below the horizontal position shown in Figures 1, 7 and 8.

50 A counterweight 22 is secured to shaft 19 in such a manner that it will cause hook 20 to stand vertically. A second shaft 23 is positioned longitudinally in body 18 and provides a support for lever 24 which is hinged at 25 to rotate about shaft 23. One or more cams 26 are provided 55 along one side of lever 24 to contact counter-

weight 22 or a similar shaped element on shaft 19.

Referring to Figure 5, it will be noted that counterweight 22 is of such size that it will maintain hook 20 vertically and will cooperate with cams 26 on lever 24 to extend that lever horizontally outwardly through slot 27 in the side of body 15.

Referring to Figures 1 and 4, it will be noted that as a drill pipe 13 is moved outwardly along body 18 it will contact lever 24 and rotate it inwardly causing cams 26 to engage the counterweight or similar shaped member on shaft 19 to rotate that shaft and turn hook 20 to a horizontal position. By these means drill pipe 13 will automatically extend hook 20 horizontally to restrain the drill pipe from slipping off the tip of fingerboard 14.

Figures 3 and 6 illustrate a preferred arrangement of shafts 19 and 23, hinges 25 and lever 24 and show hook 20 in its vertical position.

The alternative embodiment of this invention is illustrated in Figures 7 and 8 and is of somewhat simpler form than that just described. In this arrangement hollow body 18 is provided with longitudinal shaft 19, the latter having the hook or latch 20 adapted to rotate through approximately 90° and to rest upon abutment 21 when in its horizontal or extended position. In place of the automatic actuating apparatus mentioned above shaft 19 is provided with a toothed wheel or disc 28 which extends upwardly out of body 18 as through a slot 29 to be exposed so that it may be used to turn shaft 19 and move hook 20 to an upright position. A second abutment 33 on body 18 prevents hook 20 from passing beyond a vertical position. This arrangement is such that when the force used to turn wheel 28 is removed, hook 20 will drop downwardly to a horizontal position as shown in Figures 7, 8 and 9. In operating the embodiment of Figures 7 and 8 the derrickman will move a single length or stand of pipe 13 outwardly along fingerboard 14 and body 18 until it is held by hook 20. The device will retain pipe 13 in this position indefinitely. When the operator desires to release the stand or pipe he places his foot against wheel 28 and rotates it so that hook 18 is turned vertically upward. After this length of pipe has been moved away from tip 15 by the traveling block and associated equipment 16 the operator removes his foot and hook 20 will drop to the horizontal position shown. This arrangement permits the derrickman to use both hands to handle pipe 13 and does not require the embodiment of hooks or auxiliary devices to manipulate the fingerboard tip.

The operation of the automatically actuated means for rotating shaft 19 and hook 20 is similar except that the pipe 13 itself upon contacting lever 24 and swinging it downwardly, acts to rotate hook 20 to a horizontal position to retain pipe 13 against the fingerboard tip 15. In this case the operator may release pipe 13 from hook 20 by moving the pipe out of contact with body 18, whereupon counterweight 22 will swing hook 20 upwardly or the upward motion of the pipe as it is lifted by traveling block 16 will swing hook 20 to an approximately vertical position and will release the pipe from that member.

The essential features of this invention appear to reside in the provision of a hook for a fingerboard tip, said hook being secured to a generally

longitudinally mounted shaft, the latter adapted to be rotated by gravity so that the hook may selectively be moved to a vertical or horizontal position. In one embodiment the force of gravity is controlled by the contact of the drill pipe against a lever which rotates the shaft, in the alternative embodiment the shaft is rotated to its vertical position by the foot of the operator. Although the specific constructions embodying this invention have been described and illustrated, it is to be understood that the invention is not limited to those specific devices and all such modifications and changes as come within the scope of the appended claims are embraced thereby.

I claim:

1. An attachment for a derrick fingerboard comprising a body, a shaft journalled in said body for partial rotation therein, means for restraining said shaft against longitudinal motion in said body, a hook on said shaft extending outwardly from said body transversely to the axis of said shaft, means for restricting the travel of said hook between substantially a vertical and a horizontal position, means including said hook forming an eccentric weight on said shaft to maintain said hook in one of its extreme positions under the action of gravity, and actuating means projecting from said body for turning said shaft and said eccentric weight to move said hook from one extreme position to the other.

2. An attachment for a derrick fingerboard according to claim 1 in which said actuating means comprise a second shaft in said body, a lever extending outwardly from said second-named shaft, said lever adapted to be contacted by a stand of drill pipe beside said fingerboard body to rotate said second-named shaft, and means connecting said first and second shafts to rotate said first shaft and said hook.

3. An attachment for a derrick fingerboard according to claim 1 in which said actuating means comprise a second shaft in said body, a cam on said second shaft engaging said first shaft, and a lever on said second shaft extending outwardly from said body to be engaged by a stand of drill pipe, so constructed and arranged that a pressure of said drill pipe against said lever will rotate both of said shafts and said hook to one of the extreme positions of said hook.

4. An attachment for a derrick fingerboard according to claim 1 in which said actuating means cooperate with a member on said shaft spaced from said hook to rotate said shaft and said hook.

5. An attachment for a derrick fingerboard comprising a body, a shaft journalled in said body for partial rotation therein, means for restraining said shaft against longitudinal motion in said body, a hook on said shaft extending outwardly from said body transversely to the axis of said shaft, means for restricting the travel of said hook between substantially a vertical and a horizontal position, said hook forming an eccentric weight on said shaft to maintain said hook in a substantially horizontal position under the action of gravity and a member on said shaft spaced from said hook and accessible from the outside of said body to rotate said shaft and said hook to a substantially vertical position.

JOE E. NICHOLS.
